UNITED STATES PATENT OFFICE.

CHARLES H. KOSTER, OF BROOKLYN, ASSIGNOR TO THE UNEXCELLED FIRE WORKS COMPANY, OF KINGS COUNTY, NEW YORK.

BRACKET FOR FIRE-WORKS.

SPECIFICATION forming part of Letters Patent No. 364,263, dated June 7, 1887.

Application filed March 12, 1887. Serial No. 230,716. (No model.)

To all whom it may concern:

Be it known that I, CHARLES H. KOSTER, of Brooklyn, Kings county, New York, have invented a new and useful Improvement in 5 Brackets for Attaching Fire-Works on the Exhibition Posts or Frames, of which the following is a specification.

My invention consists of a bracket-piece of wood adapted to be readily nailed to the exhibition post or frame, and having notched metal holding-plates projecting from the edges, together with cross-plates attached to the back of the base or stock of the exhibition-piece of fire-works and adapted to drop into the notches, and thus hook onto the holding-plates and form a more substantial and efficient attaching device, and at the same time not being more expensive than such as are now in use, all as hereinafter fully described, reference being made to the accompanying drawings, in which—

Figure 1 is a side elevation of the bracket-piece nailed to the exhibition-post. Fig. 2 is a side elevation of a short section of the base or stock of the exhibition-piece of fire-works, having the cross-plates attached for connection to the bracket-piece. Fig. 3 is a side elevation of the bracket-piece and of the section of the base or stock of the fire-works piece as 30 they are connected on the exhibition post or frame. Fig. 4 is a front elevation of the bracket-piece, and Fig. 5 is a rear elevation of the section of the stock of the fire-works piece having the cross-bars to connect it with the bracket-piece. Fig. 6 is a front elevation of the stock of the exhibition-piece attached to the bracket. Fig. 7 is a side elevation of the bracket and the stock of the exhibition-piece attached to a post, on an enlarged scale. Fig. 8 is an elevation of an exhibition-piece of fire-works, with the cross-plates attached as for mounting on the bracket. Fig. 9 is a top view of the bracket.

The various forms of exhibition-pieces of fire-works, as A, have a base-piece or stock, *a*, consisting of a vertical bar of wood, of suitable dimensions, for the support of branches and other parts making up the whole piece, the size of the bar varying according to the size and complexity of the piece. At a suitable point along 45 this base-piece and on one side I attach two

cross-plates, *b*, of thin metal a suitable distance apart and parallel to each other, and being a little longer than the width of the bar to project a little beyond each edge, said plates being attached either on the surface of the bar or in slight gains or notches flush with the surface. Then I make a bracket-piece, *c*, consisting of a short bar of wood equal in width to that of the base-piece, and fit it with the notched holding-arms *d*, projecting from each edge at 55 right angles to the front and near each end of the bracket-piece, the notches being in the upper edges of the arms and flush with the front surface of the bracket-piece, so that by placing the base-piece *a* against the front of the bracket-piece, with the cross-plates over the arms, and letting the base-piece drop the cross-plates will drop into the notches, and the exhibition-piece will thereby be firmly attached to the post *j* or frame, the bracket-piece having been nailed thereto, and by lifting the exhibition-piece so as to raise the cross-plates above the notched arms the piece will be as 60 readily removed. At the same time the holding is very substantial, by reason of the binding of the cross-plates each side of the base-piece firmly to the surface of the bracket-piece by the "draw" of the cross-plates thereto by 65 the inclines of the notches. 70

The notched arms may consist of separate 75 plates nailed on the edges of the bracket-piece; but I prefer to form the two arms of each pair on the projecting portions of a single plate, *g*, placed across the back of the bracket-piece and bent around the edges as I have represented 80 them in the drawings. These exhibition-pieces have frequently to be taken down and be re-mounted several times for protection from rain when the weather is unfavorable, and sometimes have to be removed in great haste for 85 protection from sudden showers, which renders it of the greatest importance to have substantial and yet cheap mounting devices of the most ready action.

To facilitate the inserting of the base-piece 90 between the holding-arms, which often has to be done in the dark, I curve out the ends of the holding-arms, as at *e*, to widen the opening greater than the width of the base-piece, and so that the upper cross-plate will not lodge 95 100

on the top of the bracket-piece *c*, I taper the upper corner, *f*, of the latter.

If the cross-plates are to be nailed directly on the surface of the base-piece, the bracket-piece may be made as much thinner as the thickness of said plates where they bear against the bracket-piece, so that the surfaces of said pieces will bear together elsewhere, as is represented by the bracket-piece in Fig. 3.

10. What I claim, and desire to secure by Letters Patent, is—

1. In apparatus for mounting fire-works for exhibition, the combination, with the base or stock *a* of the exhibition-piece of fire-works having the cross-plates *b*, of the bracket-piece *c*, having the notched arms *d*, adapted to embrace the edges of stock *a* and to receive the

projecting ends of the cross plates, said bracket-piece being attached to a post with the notches of the arms upward, substantially as 20 described.

2. In apparatus for mounting fire-works for exhibition, the bracket-piece *c*, having the notched arms projecting frontward from its edges and being bent outward or widened at 25 the ends, in combination with the base-piece having the cross-plates, with projecting ends adapted to engage the notches of the arms, substantially as described.

CHARLES H. KOSTER.
